UNITED STATES PATENT OFFICE.

CECIL JOSEPH NEWHOUSE, OF MOUNDS, OKLAHOMA.

WASHING-MACHINE.

1,391,571.

Specification of Letters Patent. Patented Sept. 20, 1921.

Application filed July 28, 1920. Serial No. 399,531.

To all whom it may concern:

Be it known that I, CECIL J. NEWHOUSE, a citizen of the United States, residing at Mounds, in the county of Creek, State of Oklahoma, have invented certain new and useful Improvements in Washing-Machines; and I do hereby declare the following to be a full, clear, and exact description of the invention, such as will enable others skilled in the art to which it appertains to make and use the same.

This invention relates to new and useful improvements in washing machines and particularly to machines for washing clothes.

One object of the invention is to provide a novel and improved machine of this character which combines the features of the rotary agitator and the reciprocating pounder in a new and novel manner.

Another object is to provide a novel and improved driving mechanism for the rotary agitator and the reciprocating pounders whereby the clothes will be continuously turned in the tub and at the same time be acted upon by the reciprocating pounders.

Other objects and advantages will be apparent from the following description when taken in connection with the accompanying drawings.

In the drawings:

Figure 1 is a side elevation of a washing machine, partly in section, and made in accordance with the invention.

Fig. 2 is a top plan view of the machine.

Fig. 3 is a vertical sectional view through the upper part of the machine, taken on the line 3—3 of Fig. 2, showing the actuating mechanism in elevation.

Referring particularly to the accompanying drawings, 10 represents a tub which is preferably made of metal, and formed on the bottom of the tub, and depending therefrom, is a casing 11 in which is disposed a heating device, such as the lamp 12, for the purpose of initially heating the water, and to maintain the same at the desired temperature while the washing operation is being performed. A thermometer 13 is mounted on the side of the tub for registering the temperature of the water.

On the top of the tub are mounted the longitudinally alined bearing brackets 14 which rotatably support the shaft 15, said shaft having a fly wheel 16 on its outer end, and a pinion or gear 17 on its inner end.

It will be noted that the shaft 15 has its inner end terminating adjacent the center of the top of the tub. Longitudinally alined bearing brackets 18 are mounted on the top of the tub, at the approximate center thereof, and rotatably supported in said brackets and in parallel relation to the shaft 15, is a short shaft 19. This shaft 19 has mounted on its intermediate portion a gear 20 which has the peripheral teeth 21 meshing with the teeth of the gear 17, and the side teeth 22 meshing with the teeth of the horizontal gear 23, carried by the upper end of the vertical agitator shaft 24. The shaft 24 depends within the tub and engages with the clothes to keep them in continuous rotation, and has the radially extending dasher arms 25 formed thereon.

Mounted on the top of the tub, and on opposite sides of the shaft 19, are the supports 26, and centrally pivoted on the upper end of each support is a rock lever 27. Pivotally connected to the inner end of each rock lever 27 is a link 28 which has its other end pivotally connected to a crank 29 formed centrally on the shaft 19, and whereby, when said shaft 19 is rotated the rock levers will be moved on their pivotal supports. Connected to the outer ends of the levers 27 by means of the cushioning springs 30, are the upper ends of the pounder rods 30, the lower ends of which are disposed within the tub and are provided with the cone suction cups 31. The rods 30 are slideable vertically through suitable packings 32, in the top of the tub.

On one end of the shaft 19, is a crank handle 33, adapted to be grasped by the hand of the operator to rotate the gear.

Pivotally mounted in a bracket 34, on one side of the tub, is an upwardly extending lever 35, the intermediate portion of which is pivotally connected with a link 36 which extends toward the center of the tub and is pivotally connected to the crank 29.

Thus, by rocking the lever 35 back and forth, on its pivot, the link 36 will cause the gear 20 to rotate the agitator, the fly wheel, and rock the levers 27, through the links 28, which in turn will reciprocate the pounders. The general result will be that the agitator will continuously rotate the clothes in the tub, while at the same time the pounders will act thereon to force the water and soap back and forth through the clothes. Each time that the pounders descend they engage

with a different portion of the clothes, with the result that the wear and tear on the clothes is reduced to a minimum, while at the same time the effective cleansing there-
5 of is accomplished. If desired, the opera-
tion may be performed by grasping the
crank handle and rotating the gear 20.

What is claimed is:

10 The combination with a receptacle, sup-
ports mounted on the receptacle, a horizontal
shaft carried by the supports, said shaft
having an intermediate crank, a second hori-
zontal shaft adjacent the first shaft, inter-
meshing gears on the shafts, a pair of up-
15 rights on the receptacle, a rock lever mount-
ed on each upright, a vertical plunger rod

through the top of the receptacle, a spring
carried by the rod and connected with one
end of a rock lever, the other end of each
rock lever being pivotally connected to said
crank, a vertical rotatable shaft operatively
engaged with the first horizontal shaft, a
rock lever mounted on one side of the recep-
tacle, and a pitman connected with the said
rock lever and the said crank. 20

25 In testimony whereof, I affix my signature, in the presence of two witnesses.

CECIL JOSEPH NEWHOUSE.
